CLAIM

The ornamental design for a female connector for a cleaning head, as shown and described.

DESCRIPTION

FIG. 1 is a front perspective view of a female connector for a cleaning head showing our new design;
FIG. 2 is a rear perspective view thereof;
FIG. 3 is another rear perspective view thereof;
FIG. 4 is front view thereof;
FIG. 5 is a rear view thereof;
FIG. 6 is a right side view thereof;
FIG. 7 is a left side view thereof;
FIG. 8 is a top view thereof; and,
FIG. 9 is a bottom view thereof.

The broken lines, including broken lines showing environment of the female connector for a cleaning head, form no part of the claimed design.

1 Claim, 8 Drawing Sheets(56)
